UNITED STATES PATENT OFFICE.

CLAUD E. FULLER, OF NEW YORK, N. Y., ASSIGNOR TO AMERICAN EQUIPMENT COMPANY, OF CHICAGO, ILLINOIS, A CORPORATION OF OHIO.

CRANE.

Application filed January 4, 1922. Serial No. 526,904.

To all whom it may concern:

Be it known that I, CLAUD E. FULLER, a citizen of the United States, and resident of New York, in the county of New York and State of New York, have invented an Improvement in Cranes, of which the following description, in connection with the accompanying drawings, is a specification, like letters on the drawings representing like parts.

My present invention relates to cranes or hoisting mechanism and is particularly directed to improve and perfect a hoisting crane for use in handling brick setters or the like wherein it is important and desirable to maintain the article, machine, apparatus or load being hoisted in a predetermined position, preferably horizontal.

My invention is particularly directed to a crane or hoisting apparatus wherein it is important to maintain the load horizontal, such for example, as in brick handling, where the brick are arranged in stacked relation in units, which stacked units must be maintained horizontal during the hoisting, lowering and handling operations. In carrying out my invention I preferably provide a portable rotatable crane or hoisting apparatus, wherein the hoisting boom is provided with an automatic levelling device and whereby the carrier for the load, setter or the like is maintained at all times in horizontal position, irrespective of the raising, lowering or swinging of the boom. I also provide means to maintain this automatic levelling device in predetermined position, which means acts automatically throughout the entire range of the lowering and raising of the boom as well as during the rotation or other handling of the same. In the preferred embodiment of my invention, I apply adjacent the end of the hoisting boom, a frame, pivotally mounted and supported, one end of this frame being connected with a member which will act upon the frame automatically, to hold such frame in its predetermined position throughout the entire range of movement of the boom. I accomplish this result in an efficient manner by a pivotal connection between the frame and the rotatable part of the crane, this pivotal connection being in predetermined and spaced relation with respect to the pivot of the boom and the pivotal support of the frame.

In my present invention I find it practical and advisable to provide a four point suspension from the crane boom of the article, apparatus, brick setter or the like to be handled, the flexible cables constituting the suspending devices being led over a plurality of pulleys suitably spaced and positioned on the frame and thus affording a constantly maintained horizontal support through which the hoisting ropes are led and from which the article being handled is sustained in its horizontal position, throughout the entire range of movement of the boom, both vertically and rotatably.

Further features, novel combinations of parts and important advantages will be hereinafter more fully pointed out and claimed.

In the drawings, illustrating a preferred embodiment of my invention,

Fig. 1 is a side view;

Fig. 2 is a partial plan view, on an enlarged scale, of the outer end of the boom and levelling frame;

Fig. 3 is a side view of Fig. 2, and

Fig. 4 is an end elevation.

Referring to the drawings, 10 designates a portable support or platform on which is secured a base 11, the circular top of which forms a roller race for rollers 12. Rotatably mounted on such rollers 12 is a crane base 13 to one end of which is secured, by shaft 14, the lower end of an inclined mast 15. Guy rods or bars, but one of which, 16, is shown, are secured to the upper end of the mast 15 and to the end of the crane base 13, remote from the shaft 14. Pivotally mounted on the shaft 14 is the lower end of a crane boom 17, which boom extends outwardly from the mast 15 to any required or suitable distance. Near the outer end of this boom 17 is pivotally mounted a frame 18 in which are rotatably mounted sheaves 19. At the upper end of the mast 15 are rotatably mounted sheaves 20, in alinement with the sheaves 19. A wire cable 21 passes over the sheaves 19 and 20 and over a hoisting drum 22 mounted in a cabin 23 on the crane base 13 and driven from any suitable source of power, and by means of which the boom 17 may be raised or lowered.

On the outer end of the boom 17 and extending transversely thereof, is a shaft 24 and rotatably mounted on this shaft is a

frame comprised of side members 25 bent, as shown, to form an obtuse angle, with the pivot point at the apex of the angle, these side members 25 being spaced apart 5 and secured in position relative to each other by cross bars or plates 26, the frame being strengthened by bars 27 secured at either end to the ends of the side members 25. Rotatably mounted at the end of the 10 side members 25, that extend upwardly from the boom 17, is a shaft 28 provided at its ends with sheaves 29. Secured to the inclined mast 15 are brackets 30 forming bearings for a shaft 31 having sheaves 32 15 secured to the ends thereof. Secured to the sheaves 29 and 32 and extending therebetween are guy cables 33, a turn buckle 34 near the inclined mast 15 being provided for each cable. The distance between the 20 shafts 14 and 24 for the boom 17 is equal to the length of the cables 33, that is, equal to the distance between the shafts 31 and 28. Also, the distance between the shafts 24 and 28 is equal to the distance between the 25 shafts 14 and 31. The boom, cables 33, and the portions of the frame, including the side members 25 and mast 15, form a parallelogram having opposite sides equal, and regardless of the extent of movement of the 30 boom 17 on its pivot shaft 14, the opposite sides of such parallelogram will always be parallel to each other. With the construction above described therefore, if we make the angle formed by the side members 25 35 such that the portions of such side members extending outwardly from the shaft 24 lie in a horizontal plane, it will be evident that such portions will lie in a horizontal plane regardless of the extent of 40 movement of the boom 17 about its pivot shaft 14.

Secured to that portion of the side members 25 extending outwardly from the end of the boom 17 and lying parallel to and in 45 the same horizontal plane as the shaft 24, and spaced apart therefrom, is a shaft 44, on which is rotatably mounted at either end thereof sheaves 35 in alignment with sheaves 36 rotatably mounted on the shaft 24. Also 50 mounted on the shaft 24 and exterior of the sheaves 36 are sheaves 37. Cables 38 and 39 are secured at one end to a winding drum 40 in the cabin 23, and cable 38 passes over the sheaves 37, while cable 39 passes over the 55 sheaves 26 and 35 and extend downwardly, as shown in Figs. 1 and 3. Attached to the lower ends of the cables 38 and 39, of which there is a total of four, is a load carrying device 41, in the drawings this device being 60 shown as a rotatably mounted carriage

adapted to transport a unit of brick 42. As, however, the details of construction of the device 41 do not concern the present invention, it will not be described in detail herein, it being understood that any load carrying device may be attached to the cables 38 and 39 and suspended from the pivoted frame 25. As the winding drum 40 reels in and lets out the cables 38 and 39 equally, the device 41 will be maintained in a horizontal plane provided the support therefor is maintained horizontal, and as, by reason of the method of mounting the frame 25 in position on the boom 17 ensures that the portion of said frame 25 extending outwardly from the boom 17 is maintained in a horizontal plane, the device 41 will be maintained at all times in a horizontal position, regardless of the position of the boom 17.

It will be apparent that the automatic levelling features of my present invention may be applied to different types of cranes and hoisting members or apparatus, though I have here shown such features as applied to a rotatable, portable hoisting frame, particularly adapted for the handling of a brick setter, wherein it is desirable and necessary that the brick units be maintained in horizontal position.

While I have shown and described the preferred embodiment of my invention somewhat in detail, it is to be understood that I may vary the size, shape, and arrangement of parts comprising my device within wide limits without departing from the spirit of the invention.

Having thus described my invention, what I claim as new, is:—

Hoisting apparatus of the kind described, comprising, in combination, a base, a mast mounted on, and in fixed relation thereto, a boom pivotally mounted on the base at the foot of the mast, a frame including two bell crank levers arranged parallel to, and spaced apart from, each other, pivotally mounted on the free end of the boom at the apex of the bell crank levers, means arranged at the ends of the pivotal mounting of the bell crank levers and at the ends of one of the arms of said levers, and constituting a four-point suspension for a work support, and means extending from the free ends of the other arms of the bell crank levers to the mast for maintaining the four-point suspension means in planes bearing a constant relation to a horizontal plane.

In testimony whereof, I have signed my name to this specification.

CLAUD E. FULLER.
